UNITED STATES PATENT OFFICE.

CARROLL W. DODGE, OF WORCESTER, MASSACHUSETTS, ASSIGNOR TO
WILLIAM R. ALBERTSON, OF SAME PLACE.

MARKING-KIT.

SPECIFICATION forming part of Letters Patent No. 545,949, dated September 10, 1895.

Application filed May 2, 1895. Serial No. 547,838. (No model.)

To all whom it may concern:

Be it known that I, CARROLL W. DODGE, a citizen of the United States, residing at Worcester, in the county of Worcester and 5 State of Massachusetts, have invented a new and useful Marking-Kit, of which the following, together with the accompanying drawings, is a specification sufficiently full, clear, and exact to enable persons skilled in the art 10 to which this invention appertains to make and use the same.

My present invention relates to a utensil of the class employed for marking addresses on shipping-cases and for similar purposes; and 15 it consists in certain improvements in the construction and adaptation of the component parts of the apparatus, with the object of rendering the same more convenient, efficient, and desirable for use, and better adapted 20 for preserving the ink and brushes in suitable condition for ready use.

The particular features of improvement which constitute my invention are hereinafter definitely specified.

25 In the drawings, Figure 1 is a perspective view of my improved marking-kit. Fig. 2 is a vertical central section of the same. Fig. 3 is a top view with the hand tube or stem in section. Fig. 4 is a separate detail view on 30 somewhat larger size, showing a section of the dip-funnel and its covering-cap. Fig. 5 is a detail section through the hand-tube, showing the internal ledge and the removable pointing-tube; and Fig. 6 shows a plan and 35 section of the ledge or washer-plate.

Referring to parts, A denotes the ink container or reservoir, consisting of a flat cylindrical can formed of sheet metal, its top portion a and sides a' preferably integral and stamped 40 or swaged into the desired shape, while the bottom plate A² is preferably formed with a flange or fold at its periphery, which is inserted and soldered into the rim around the bottom edge, the combined edges forming a foot 45 for the can, as at E. The bottom is best formed with a depression, as at a³.

C indicates the dip-funnel in the top of the container, and into which the brush B is inserted for taking ink. This dip-funnel is 50 made with an interior downward tapering

portion that reaches nearly to the bottom of the ink - container and terminates with an open end c; also with an upwardly-projecting portion C' above the top-plate a, having an opening or mouth c², surrounded by an inwardly-turned lip c³, against which the brush B may be drawn for removing excess of ink as it is lifted from the funnel-cavity. The dip-funnel is supported in an opening formed through the top plate a, and is soldered or otherwise tightly secured thereon at the joint e. 55

D indicates a metal cap which is arranged to fit over the upper end of the dip-funnel C. Said cap is provided with an attached rubber washer d, having a hole therein through 65 which the handle of the marking-brush B is inserted, the washer and cup-shaped cap being thus fixed upon the brush-handle to be used as a finger-guard to keep ink from the fingers when marking cases and to serve as a cover 70 for the dip-funnel when the kit is not in use and as a support for the brush when in soak.

F indicates the stem or hand-tube, fixed upon the top of the container, near its edge, by a reinforce f and rivets, or in other suitable 75 manner. Within this stem, which is hollow, closed at its bottom and open at its top, I arrange a horizontal ring or annular ledge I about the the interior for the support of the cap D and brush B, in the manner illustrated 80 in Fig. 2, said ledge preferably having an opening i through its center, with a downwardly-beveled edge 5. This ledge can be readily made by introducing a flat annular washer (I', Fig. 6) into the tube F and then 85 swaging the parts together to give rigid fixation at the periphery of the washer. The lower chamber G within the hand-tube serves for containing water or other liquid for soaking out or maintaining the brushes in pliable 90 condition. The cap D, resting on the ledge, supports the brush upright with its end clear from the bottom. The ledge I also prevents the liquid from splashing over the top of the hand-tube when the marking-kit is carried 95 about in use.

M indicates a pointing-tube having a flanged or flaring top end m, and adapted to be removably suspended within the chamber G by resting on the ledge I or its beveled surface 100

within the central opening *i*, as shown. The pointing-tube is formed with a long taper and has a small opening *n* in its lower end. When the brush is inserted in the pointing-tube, the hairs thereof are supported and straightened, and the brush is thereby kept in form. The pointing-tube may be perforated, as at *r*, near its upper end, so that the water can enter from the chamber and flow down the interior to soak the brush. In any instance, if desired, this removable pointing-tube can be omitted, the brushes being merely introduced directly into the chamber *G* through the opening *i* for keeping them in condition. To facilitate filling, the container *A* may have the usual opening with a screw-cap or stopper, as *P*.

With the marking-kit constructed as described, the brush can be left standing in the dip-funnel always ready for use, without liability of curling the point of the brush. Two sizes of brushes can also be employed, when desired, without drying up, one being kept inserted in the chamber *G* and the other in the dip-funnel and alternating them as required for use.

Utensils for inks and colors having been heretofore constructed with a flat cylindrical stem or hand-tube thereon, I do not herein claim, broadly, such features; but my invention embraces the specific improvements hereinafter defined.

I claim as my invention and desire to secure by Letters Patent—

1. In a marking kit, in combination with the ink-container consisting of the closed metal can having the flat top-plate, the dip-funnel rigidly fixed in said top-plate with an upwardly projecting exterior portion, having its top edge turned over and forming an inwardly directed lip about the mouth, substantially as set forth.

2. In a marking kit, the hollow stem or hand-tube fixed to the ink-container and provided with an annular ledge or supporting shelf about its interior, said shelf disposed at some distance below the top of said hand-

tube, as shown, and with a chamber beneath said ledge, for the purpose set forth.

3. In a marking kit, the hollow-stem having the annular inwardly directed ledge therein, with a chamber for liquid below, and the removable pointing-tube having the flared or open flanged end supported on said ledge, with its smaller end depending within said chamber, for the purpose set forth.

4. In a marking kit, the brush provided with a finger-guard adapted as a cap for the dip-funnel of the container; in combination with the dip funnel fixed in the ink container, and having the projecting top, and the hollow stem having, in its interior, means for supporting said cap with the brush suspended within the chamber below said point of support, for the purpose set forth.

5. The ink-container, composed of the sheet-metal top-plate and rim, and the bottom-plate formed with the downward peripheral flange secured within said rim, and having the depression therein; in combination with the dip-funnel secured in the top-plate with its lower end opening to the interior adjacent to the bottom above said depression, the removable cap fitting over the top of said dip-funnel, and the brush supported in said cap, as shown and described.

6. In combination with the ink-container having the dip-funnel arranged therein, its upper portion projecting above the top-plate, the upright stem or hand-tube fixed to said container, and having the open top, and the inward offset or ledge about its interior, with a chamber for containing liquid below said ledge, the cap adapted for covering said dip-funnel and for sustention upon said ledge within the hand-tube, and the marking-brush, its handle passing through and supported in said cap, substantially as set forth.

Witness my hand this 27th day of April, 1895.

CARROLL W. DODGE.
